UNITED STATES PATENT OFFICE.

ROBERT B. KUHN, OF CANTON, OHIO.

TANK.

1,157,643.

Specification of Letters Patent.

Patented Oct. 19, 1915.

Application filed June 23, 1914. Serial No. 846,823.

To all whom it may concern:

Be it known that I, ROBERT B. KUHN, a citizen of the United States, residing at Canton, in the county of Stark and State of Ohio, have invented certain new and useful Improvements in Tanks, of which the following is a specification.

The invention relates to tanks for carrying gasoline and other liquid fuels in automobiles, motor trucks, motor boats, and like uses; and the object of the improvement is to provide means for preventing a draining of all the liquid fuel from the tank through its ordinary outlet, and to provide means for separating water and other liquid or solid refuse from the liquid fuel, so that the same will not be carried into the discharge pipe.

These objects are attained by providing an open sump below the bottom of the tank for receiving the water and other refuse which settle from the liquid fuel; and by providing an ordinary outlet opening from the tank above its bottom, and an auxiliary outlet opening from the sump above its bottom, and a common discharge pipe leading from the outlets with a controlling valve at the junction thereof.

A preferred embodiment of the invention, thus outlined, is illustrated in the accompanying drawings, forming part hereof, in which—

Figure 1 is a side elevation section of the bottom portion of a tank showing the improvements applied thereto; Fig. 2, a fragmentary under side plan view of the same; and Fig. 3, a fragmentary bottom plan view of the same.

Similar numerals refer to similar parts throughout the drawings.

The tank 1 is provided with the pendent sump 2 secured to the bottom of the tank and opening freely downward therefrom. The three-way valve case 3 is provided at one side of the sump, in which case is formed the port 4 opening downward from the tank, the port 5 opening from the side of the sump above the bottom thereof, and the port 6 communicating with the discharge pipe 7.

The valve 8 in the case 3 is provided with the port 9, which may lead either from the tank port 4 or the sump port 5 to the discharge port 6 by a proper turning of the valve, or the valve may be turned to entirely close the discharge port.

The outlet from the tank is preferably

formed by the stand pipe 10 rising from the tank port in the valve case, and having its upper end curved laterally and downward so that the receiving mouth 11 of the outlet is presented downward to require the liquid fuel to flow upward when entering the same; thus preventing undue agitation of the liquid fuel in the bottom of the tank, so that the water and other heavy refuse may settle therein.

The sump port 5 forms an auxiliary outlet from the side of the sump above the bottom, and preferably extends laterally upward therefrom so that its receiving mouth 12 is directed downward to require the liquid fuel to flow upward when entering the same; thereby preventing an agitation in the bottom of the sump so that water and other heavy refuse will settle therein.

The deflecting flange 13 is preferably provided in the side of the sump above the mouth 12 of the outlet port, for the purpose of requiring the liquid to flow downward toward the bottom of the sump before passing upward into the downwardly presented mouth of the outlet, so that water and other refuse will more certainly sink to the bottom of the sump, whence it may be drawn off from time to time, by the pet-cock 14 leading therefrom.

In the use of the tank, the same being filled with gasoline or other liquid fuel, the valve 8 is turned so that its port 9 leads from the tank port 4 to the discharge port 6, in which relation of the parts the sump port 5 is closed, as shown in Fig. 1, of the drawings. The water and other comparatively heavy refuse contained in the liquid fuel, settle by gravity to the bottom of the tank below the mouth 11 of the outlet therefrom, and ultimately find their way into the bottom of the sump, so that only free liquid fuel will be drawn off through the outlet from the tank.

When the level of the liquid fuel in the tank falls below the mouth of the outlet pipe therein, the tank may either be refilled, or the valve 8 may be turned so that the port 9 therein will lead from the sump port 5 to the discharge port 6, for drawing off the remainder of the liquid fuel remaining in the bottom of the tank and the top of the sump, without drawing off the refuse which may have settled in the sump below its outlet.

It will be understood that in the use of

the tank, it is desirable to open the pet-cock 14 from time to time, to draw off the sediment and water as the same accumulates therein, so that ordinarily there will be no water or refuse in the sump above the mouth 12 of the auxiliary outlet, so that when it becomes necessary to draw off the liquid fuel from the bottom of the tank and top of the sump, the same will be substantially free from water and refuse.

I claim:

1. A tank having a sump below and in open communication with the bottom thereof, a discharge pipe, an outlet leading from the tank to the discharge pipe having its receiving mouth above the bottom of the tank, and an outlet leading from the sump to the discharge pipe having its receiving mouth above the bottom of the sump and below the bottom of the tank.

2. A tank having a sump opening downward from the bottom thereof, a discharge pipe, an outlet leading from the tank to the discharge pipe having its receiving mouth above the bottom of the tank, and an outlet leading from the sump to the discharge pipe having its receiving mouth above the bottom of the sump, and a controlling valve at the junction of the outlets with the discharge pipe.

3. A tank having a sump opening down-

ward from the bottom thereof, a discharge pipe, an outlet leading from the tank to the discharge pipe having a downwardly presented receiving mouth above the bottom of the tank, and an outlet leading from the sump to the discharge pipe having a downwardly presented receiving mouth above the bottom of the sump.

4. A tank having a sump opening downward from the bottom thereof, a discharge pipe, an outlet leading from the tank to the discharge pipe having a downwardly presented receiving mouth above the bottom of the tank, and an outlet leading from the sump to the discharge pipe having its receiving mouth above the bottom of the sump.

5. A tank having a sump opening downward from the bottom thereof, a discharge pipe, an outlet leading from the tank to the discharge pipe having its receiving mouth above the bottom of the tank, and an outlet leading from the sump to the discharge pipe having its receiving mouth above the bottom of the sump, there being a deflecting flange in the sump above the receiving mouth of its outlet.

ROBERT B. KUHN.
